DESIGN FOR A SHOE HEEL

Wendell Stafford, Effingham, Ill., assignor to Vulcan Corporation, Portsmouth, Ohio, a corporation of Ohio

Application October 29, 1938, Serial No. 80,766

Term of patent 7 years

To all whom it may concern:

Be it known that I, Wendell Stafford, a citizen of the United States, residing at Effingham, in the county of Effingham, State of Illinois, have invented a new, original, and ornamental Design for a Shoe Heel, of which the following is a specification, reference being had to the accompanying drawing forming a part thereof.

In the drawing:

Fig. 1 is a side elevational view of a shoe heel, showing my design.

Fig. 2 is a perspective view thereof.

Fig. 3 is a longitudinal sectional view of the heel taken on line 3—3, Fig. 1.

Fig. 4 is a bottom perspective view of the same.

Fig. 5 is a cross-sectional view, taken on line 5—5, Fig. 1.

I claim:

The ornamental design for a shoe heel, as shown.

WENDELL STAFFORD.
